UNITED STATES PATENT OFFICE.

CHARLES ELLSWORTH ADAMSON, OF BUFFALO, NEW YORK.

SELF-HEATING SAD-IRON.

1,025,502.

Specification of Letters Patent.

Patented May 7, 1912.

Application filed April 30, 1908. Serial No. 430,059.

To all whom it may concern:

Be it known that I, CHARLES ELLSWORTH ADAMSON, a citizen of the United States, residing at Buffalo, in the county of Erie 5 and State of New York, have invented certain new and useful Improvements in Self-Heating Sad-Irons, of which the following is a specification.

My invention relates to improvements in 10 self-heating sad-irons and more especially to rolling or revolving irons.

The primary object of my invention is the production of a sad-iron formed in one integral piece and embodying in its construction 15 a heating-chamber and means to receive and hold an absorbent material in such relation to said heating-chamber as to provide a flame within the latter.

Another object is, the production of a 20 simple and effective self-heating rotatable sad-iron in which a heating-chamber is formed or applied centrally in said iron.

To these ends the invention consists in a 25 revolvably-supported roller serving as the sad-iron and hollowed out to provide a heating-chamber and also bored to receive absorbent material adapted to be saturated with alcohol or any suitable hydrocarbon; it also consists in the construction, arrangement and combination of parts to be herein- 30 after described and particularly pointed out in the appended claims.

In the drawings,—Figure 1 is a plan view 35 of my improved sad-iron. Fig. 2 is a side elevation of the same viewed from the open end thereof. Fig. 3 is a sectional plan view of the iron; the sectional portion being taken on line 3—3, Fig. 2. Fig. 4 is a sectional elevation of the iron; the sectional portion 40 being taken on line 4—4, Fig. 1.

Referring now to the drawings in detail, similar letters of reference refer to similar parts in the several figures.

I prefer to make the sad-iron in the form 45 of a roller, so as to have a small bearing area, which enables the user to apply great pressure to the goods with the least amount of weight in the iron. I make the roller A of a suitable metal and provide a suitable 50 handle B and frame C, all as shown in the drawings. In one end of the roller A I provide a heating chamber which is formed by drilling or boring out the central portion

of the roller to about one-fourth its length, forming a recess or bowl D, most clearly 55 shown in Figs. 2 and 3. I then drill a plurality of holes or bores E around the axis of the roller from this recess almost through to the other end of the roller, which holes or bores serve as pockets to receive absorbent material F, such as ordinary cotton wicking, as shown in Figs. 2, 3 and 4; that portion of the iron having the bores forming a burner. In this manner, the roller is formed in one integral piece and embodies 65 in its construction a burner and a heating-chamber, and in providing the pockets and wicks in the roller, I regulate the size and number so as to hold just enough liquid-fuel to heat the roller properly to begin ironing. 70 Thus it will be seen that I can regulate the heating capacity of the burner by the number and size of these absorbing wicks. I regulate this according to the size of the iron to be heated. 75

To each end of the roller A, I provide screw-journals G, which serve to support the roller in the frame or yoke C, most clearly 80 shown in Figs. 2 and 3. I connect the yoke or frame C to the handle B in any common or suitable manner. In using my invention or in preparing the iron for use, a small quantity of wood alcohol or a fluid-hydrocarbon is poured into the bowl D, which is at once absorbed by the wicks F. I pour 85 out all that is not absorbed. The iron is then laid down flat and a match applied to the open end thereof to ignite the liquid-fuel, which burns slowly for about three minutes, during which time the open end of 90 the iron becomes heated.

As soon as the interior flame heats the inner surface of the metal and the wicks sufficiently to create a vapor or gas from the liquid-fuel the flame will at once greatly increase. 95 The iron is then picked up and turned with the open end down so that the flame will encircle the iron, burning sufficiently long to heat it just right for use. My iron can be used for regular ironing, the same as any flat iron, but it is more especially adapted to be made small and portable so as to be carried in the pocket or grip and used by people traveling. 100

I do not wish to confine my method of 105 heating to a rotary iron, as it may be ap-

plied to other shapes, and I do not limit the heating chamber to any particular number or form of absorbing wicks, but

What I do claim and desire to secure by Letters Patent is,—

- 5 1. A self-heating rotatable iron comprising a cylindrical body hollowed at one end to form a heating-chamber and having a pocket extending from said chamber toward its other end, and absorbent material within said pocket.
- 10 2. A sad-iron comprising a cylindrical roller hollow at one end to form a heating-chamber and having pockets around the axis 15 of the roller extending from said chamber toward the other end of the roller, absorbent material in said pockets, and a handle in which said roller is rotatably held.
- 20 3. A rotatable sad-iron comprising a cylindrical body having an open heating-chamber at one end extending through a portion of its length and a pocket extending

from said chamber lengthwise toward the opposite end of said body, and absorbent material in said pocket and exposed through 25 said open heating-chamber.

4. A rotatable sad-iron comprising a one-piece cylindrical body having a pocket formed therein and a heating-chamber into which said pocket opens, and absorbent material held in said pocket. 30

5. In a self-heating sad-iron, a hollow body portion having a pocket or pockets and a heating chamber formed therein, said pocket or pockets extending inward from 35 said heating chamber, and absorbent material retained in said pocket or pockets.

In testimony whereof, I have affixed my signature in the presence of two subscribing witnesses.

CHARLES ELLSWORTH ADAMSON.
